UNITED STATES PATENT OFFICE.

LAES J. PARKER, OF CHICAGO, ILLINOIS, ASSIGNOR TO QUALITY HARDWARE & MACHINE CO., A COPARTNERSHIP CONSISTING OF JERRY ANDERSON, H. A. LAYSTROM, C. A. LAYSTROM, CARL SCHWARTZ, MRS. LOUISA LAYSTROM, FRANK LINDGREN, ELSIE LAYSTROM, AND EVELYN PETERSON.

TELESCOPIC PUNCH FOR FORMING TUBES.

Application filed August 26, 1927. Serial No. 215,556.

This invention relates to pressure applying devices, commonly known as punches, which cooperate with dies to produce from sheet metal sundry hollow shapes.

5 It is a primary object of this invention to provide a punch adapted to the production of closed elongated tubes from shallow metal forms or cups in a single operation.

10 It is another object of this invention to provide a punch having sliding members in telescopic relation adapted to offer a series of stepped pressure applying faces as the punch progresses through a die holder to produce an article of a desired shape in a 15 single operation.

15 It is a further important object of this invention to provide a punch or pressure applying device having a plurality of slideable members which are locked together to 20 provide a pressure applying face of a desired area when the face engages with material to be formed and to unlock the members in predetermined sequence to provide a face of 25 decreasing area as the device progresses into a die holder to produce an article of a desired shape in a single operation.

Other and further important objects of 30 this invention will be apparent from the disclosures in the specification and the accompanying drawings.

This invention (in a preferred form) is illustrated in the drawings and hereinafter more fully described.

On the drawings:

35 Figure 1 is a side elevation of the device with the die holder and dies in section and shows the punch engaging the cup in the initial step of the forming operation.

40 Figure 2 is a side elevation of the device with the die holder and dies in section and shows the punch engaging the material to be formed in an intermediate step of the forming operation.

45 Figure 3 is a sectional view of line III-III of Figure 1.

Figure 4 is a sectional view on line IV-IV of Figure 3.

Figure 5 is a sectional view on line V-V of Figure 3.

50 Figure 6 is a sectional view on line VI-VI of Figure 5.

Figure 7 is a sectional view on line VII-VII of Figure 5.

Figure 8 is a plan view of the base of the die holder showing the stripper plates. 55

Figure 9 is a section on line IX-IX of Figure 8.

As shown on the drawings:

The numeral 10 indicates a shank or stem having a shoulder 11 formed by an enlarged portion 12. Pressure may be applied to the shank 10 at its upper enlarged portion 14 by any suitable means. The shank 10 is apertured as at 15 to seat a ball 17. The upper portion of the seat is cut away as shown at 16 in Figures 4 and 5 to promote unseating of the ball 17 when such unseating is proper as will be discussed later.

A sleeve 18 having a shoulder 19 formed on the upper end thereof is slidable on the shank 10.

The sleeve 18 has an inclined aperture indicated at 20 in Figure 5 alignable with the aperture 15 in the shank 10 to house the ball 17. A slot 23 in the sleeve 18 is aligned 75 with a slot 21 in the shank 10 and a key 22 feathers in the slots 21 and 23 to retain the members 18 and 10 in circumferential alignment. Threaded pins 34 in the sleeve 18 alternately engage the key 22 causing it to slide in the slot 21 and retaining it therein. The upper end of the sleeve 18 abuts against the shoulder 11 on the shank 10 to limit its travel upwardly when free to slide on the shank. The downward travel of the sleeve 18 is 80 limited by the ball 17 when it enters and is housed in the apertures 15 and 20. The sleeve 18 is also apertured at 24 on Figure 4 to seat the ball 25, for a purpose that will appear later. The aperture 24 is cut away 85 to promote the unseating of the ball seated in it, when the occasion for unseating arises as will be discussed when the operation of the device is gone into.

A second sleeve 26 having a shoulder 27 95 formed thereon at its upper end is slidable on the sleeve 18. It will be noted that the sleeve 26 closes the ball housing aperture 20 in the sleeve 18 as indicated at 28 in Figure 5, and in doing so enables the ball 17 to hold the shank 10 and the sleeve 18 in locked engagement.

It will also be noted that an aperture 29 in the sleeve 26 is capable of alignment with the aperture 15 in the sleeve 18 so that the 105 ball 17 may roll or be expelled into the

scends below the stripping fingers 61, the fingers move forward to retain the tube when the punch is withdrawn from the die holder.

5 As the punch ascends the sleeves fall into locked engagement with each other and with the stem so that at the end of the upward stroke the pressure applying face has the area it had at the beginning of the downward stroke.

10 It will be obvious that with the release of downward pressure on the shank 10 when the punch is about to be retracted the spring member 44 acting through the pin 43 on the shoulder 42 will cause a slight lifting of the sleeves and encourage the free movement of the balls in the several apertures as the punch is retracted.

15 The conduit formed in the stem permits the escape of air from the formed material as the punch descends into it. It will be understood that the device is not limited to the application shown in the drawings, and that the initial area of the pressure applying 20 face may be changed by the simple expedient of unlocking one or more of the outer sleeves.

25 I am aware that many changes may be made, and numerous details of construction 30 may be varied through a wide range without departing from the principles of this invention and I therefore do not purpose limiting the patent granted hereon, otherwise than necessitated by the prior art.

35 I claim as my invention:

1. A portable telescopic punch adapted to draw a blank of metal in a stepped die, the punch comprising a center rod member, a plurality of overlying concentric sleeves 40 in sliding engagement on the rod member, a collar slidable on the outermost sleeve, interlocking means adapted to retain the sleeves and the rod in assembled locked relation, the said collar being adapted to engage 45 an abutting surface on the die after the

punch has entered a predetermined distance therein to release certain of said interlocking means and thereby permit relative motion of the sleeves and the rod member in a predetermined sequence.

50 2. A portable telescopic punch adapted to draw a blank of metal in a stepped die, the punch comprising a center rod member, a plurality of overlying concentric sleeves in sliding engagement on the rod member, a 55 collar slidable on the outermost sleeve, interlocking ball means adapted to retain the sleeves and the rod in assembled locked relation, the said collar being adapted to engage an abutting surface on the die after the 60 punch has entered a predetermined distance therein to release certain of the said interlocking ball means and thereby permit relative motion of the sleeves and the rod member in a predetermined sequence.

65 3. A telescopic punch adapted to draw a blank in a stepped die, the punch comprising a center rod member, a plurality of overlying concentric sleeves in sliding engagement on the rod member, the said rod member 70 having a plurality of elongated recesses and the said sleeves having elongated recesses and inclined passaged apertures, a collar slidable on the outermost sleeve, the said collar having an elongated recess, interlocking ball means housed in the sleeves adapted to retain the sleeves and the rod in assembled locked relation, resilient abutment means on one of the said sleeves adapted to abut another of said sleeves when the punch is in 75 the die, the said collar being adapted to engage an abutting surface on the die after the punch has entered a predetermined distance in the die to release certain of said interlocking ball means.

80 85 In testimony whereof I have hereunto subscribed my name at Chicago, Cook County, Illinois.

LARS J. PARKER.
